BAFFLE FOR AIR-COOLED CYLINDERS

Roland Chilton, Ridgewood, N. J., assignor, by
mesne assignments, to The Reed Propeller Co.,
Inc., Garden City, N. Y., a corporation of New
York

Application February 15, 1932, Serial No. 592,998

3 Claims. (Cl. 123—171)

This invention relates to baffles for improving the cooling air flow over the cylinders of air-cooled internal combustion engines and for preventing wasted air flow in the intercylinder spaces.

Objects of the invention are to provide an improved form of baffle and a simplified securing means therefor which will be adaptable to conventional engines without the incorporation of special baffle supporting means on the cylinders. An associated object is to provide a quickly demountable attachment for the baffles which will give a minimum resistance to the air flow and to provide a system of support and baffle construction which will withstand the vibration and air loads to which these parts are subject, particularly in aircraft engines.

In the drawings:

Fig. 1 is a rear elevation showing a pair of air-cooled cylinders equipped with the baffle means of this invention, and

Fig. 2 is a section on the line 2—2 of Fig. 1.

In the drawings an adjacent pair of cylinders comprising the finned heads 10 secured to the finned barrels 12 in the usual way is shown as for a radial engine. The baffle 14 is preferably of V form as shown in Fig. 2 and may conveniently be fabricated from sheet metal. It is provided top and bottom with the turned over flanges 16 and 18 which are engaged between adjacent fins of the heads and barrels respectively, being conformed to the profile of these parts at the base of the fins so as to present an adequate length of contact.

The baffle is secured by means of a cross bridge 20 which is also engaged between a pair of fins; in this particular case at the upper fin space of the cylinder barrels. The bridge piece 20 is provided with a stud 22 around which the baffle 14 is reinforced by plate 24 against which the nuts 26 are tightened, securing the entire assembly in place.

At the back of the baffle a cross rib 28 may be secured in order to stiffen the structure, and such cross rib forms a convenient place of attachment for the forward end of the airplane cowling (not shown), for which purpose the rib 28 may be provided with studs 30.

It should be understood that in air-cooled cylinders it is very undesirable to have obstructions to the air flow through the fin spaces, and it will be seen that if the baffles were secured by studs these would require bosses which would blank out some of the spaces and thus spoil the

air flow and cooling effect of the adjacent fins. It will also be appreciated that the fabrication of such bosses in the case of cylinder barrels, wherein the fins are turned from the solid, would present considerable manufacturing difficulty. According to the present invention the thin flanges 16 and 18 produce a minimum of obstruction to the air flow. In order to work on the cylinders and other engine parts it is often necessary to remove the baffles, and it will be seen the fastening device here disclosed permits of rapid disassembly by merely unscrewing the nuts from the single stud 22.

By referring to Fig. 2 it will be seen that otherwise wasted air flow between adjacent cylinders is, by means of this baffle, deflected around to the leeward side of the cylinders, which would get poor cooling in the absence of the baffle.

It is to be understood that the above described embodiment of the invention is for the purpose of illustration only, and various changes may be made therein without departing from the spirit and scope of the invention.

I claim as my invention:

1. In an engine having a plurality of finned air-cooled cylinders, a sheet metal baffle for controlling air flow around a plurality of said cylinders, said baffle having formed at several of the edges thereof overturned flanges adapted respectively for fitting engagement between the fins of more than one of said cylinders.

2. In an engine having a plurality of finned air-cooled cylinders, a sheet metal baffle for controlling air flow around a plurality of said cylinders, said baffle having formed at several of the edges thereof overturned flanges adapted respectively for fitting engagement between the fins of more than one of said cylinders, and means bearing on more than one of said cylinders for holding said baffle in assembled relation with said cylinders.

3. In an air-cooled engine including a pair of spaced finned cylinders, a baffle spanning said cylinders on one side thereof, said baffle having bearing portions for fitting engagement between adjacent fins at the upper and lower portions of the respective cylinders, a bar spanning said cylinders lying on the opposite side thereof from said baffle and having bearing portions for fitting engagement between the fins of the cylinders, and means for adjustably clamping said bar to said baffle, said means lying in the inter-cylinder space.

ROLAND CHILTON.
